UNITED STATES PATENT OFFICE.

WILLIAM T. COLEMAN, OF SEATTLE, WASHINGTON.

AUTOMOBILE TURN-TABLE.

No. 926,388.

Specification of Letters Patent.

Patented June 29, 1909.

Application filed April 12, 1909. Serial No. 489,522.

To all whom it may concern:

Be it known that I, WILLIAM T. COLEMAN, a citizen of the United States, and resident of Seattle, in the county of King and State of Washington, have invented certain new and useful Improvements in Automobile Turn-Tables, of which the following is a full, exact, and complete specification.

My invention relates to turn-tables for use in garages for turning automobiles, and has for its object the provision of a structure consisting of metallic beams and plates having runways for the wheels of the vehicle and provided with a lug or projection in its center to seat in a socket in a plate to be secured to the floor of the garage, or in a socket in the top of a pillar secured to the bottom of a pit when desired, and having rollers on the ends having their journals arranged 20 radially of the circle described by the table in turning.

The construction of my improved turn-table will be described in detail hereinafter and illustrated in the accompanying drawings, in which—

Figure 1 is a top plan view of my improved device; Fig. 2 a longitudinal sectional view; Fig. 3, transverse section view; and Fig. 4, a view of the pillar used when a pit is 30 provided for the table.

In the drawings similar reference characters indicate corresponding parts in the several views.

The side sills of my improved turn-table 35 are constructed of angle-beams 1 and have I-cross-beams 2 secured adjacent to the ends thereof and with their bases extended at each end beyond the sills, as shown at 3, and compound angle cross-beams 4 secured at 40 each side of the middle of the sills with their bases also extended, as shown at 5. The runways are secured on the outside of the sills and tops of the extended ends of 3 and 5 of the cross-beams, and consist of angle-beams 6, with the vertical side 7 secured to the sills and the horizontal portion 8 extending laterally therefrom to form the runway for the wheels of the vehicle.

9 indicates brace-plates secured to each 50 end of I-beams 2 and sill 1, and 10 other brace-beams or plates secured at each end of the compound angle-beams 4 and sill 1, this structure forming a substantial and rigid structure that has sufficient strength to sup-

port the vehicle and withstand the wrenching incident to turning while supporting the vehicle.

12 indicates a plate secured under the top flange of compound angle-beams 4 and having the middle of its under side formed with 60 circular lug or projection 13 and the surface adjacent to the lug beveled upwardly as shown at 14.

15 indicates a hole through the center of plate 12 and lug 13, through which to lubricate the bearing formed by the lug and the socket to be hereinafter described.

When the turn-table is to be installed on the floor of the garage a plate 16 is secured to the floor, said plate being provided with a 70 central boss 17, having a socket 18 therein to receive the lug 13 in the center of the turn-table and forming the bearing for the center of the table.

19 indicates rollers journaled on bearings 75 20, adjacent to the inner sides of the ends of sills 1, the axles of said rollers being on planes forming radii concentric with the center of lug 13, it being understood that said rollers by having their bearing surfaces 80 below the plane of the underside of the turn-table operate to hold the table above the floor so that the movement of the table in turning is relieved of friction between the floor and the bottom of the table.

When my table is installed in a pit a pillar 21 is secured in the center of the pit, said pillar being provided with a socket 22 to receive the lug 13, and the rollers 19 may be arranged to travel on a circular shelf around 90 the edge of the pit or a circular track may be provided for the rollers, this structure being common in turn-tables for locomotives, etc., now in general use and considered to be unnecessary to be shown.

Having thus described my invention, what I claim is—

1. A turn-table for automobiles consisting of a frame having side sills of angle-beams, cross-beams connecting said sills, angle-beams secured to the outer sides of said sills and having their horizontal portions forming runways for the vehicles' wheels, a plate secured to the center of the frame having a downwardly-extending lug, a support for 100 the center of the frame having a socket to receive the lug, and rollers journaled adjacent to the ends of the sills and having their

axes on planes forming radii concentric with the center of the lug, substantially as shown and described.

2. A turn-table for automobiles comprising a frame having side sills of angle-beams, cross-beams of I-beam type secured adjacent to the ends of the sills and having their bases extended beyond said sills, other cross-beams of compound angle-beam type secured at each side of the middle of the sills and having their bases extended beyond the sills, angle-beams secured on the outside of the sills and on top of the extended ends of the bases of the cross-beams, the horizontal portion of the last-mentioned angle-beams forming runways, a plate secured to the

middle of the compound angle-beams, a lug extending downwardly from the said plate and forming the center of the frame, a plate having a central boss with a socket therein to receive said lug, and rollers journaled adjacent to the ends of the sills and having their axes on planes forming radii concentric with the center of the lug aforesaid, substantially as shown and described. 20
